Primary Examiner — Terry Wallace

(57) CLAIM

The ornamental design for a combined cup holder and carrier with cut-out handles, as shown and described.

DESCRIPTION

FIG. 1 is a front view of the combined cup holder and carrier with cut-out handles showing my new design, the rear view being a mirror image.

FIG. 2 is a front perspective view thereof, the rear view being a mirror image; and,

FIG. 3 is a top plan view thereof in an open position.
